UNITED STATES PATENT OFFICE.

LELAND CLAPPER, OF TWO HARBORS, MINNESOTA.

SELF-CLEARING ORE-POCKET.

1,172,007,

Specification of Letters Patent. Patented Feb. 15, 1916.

Application filed July 30, 1914. Serial No. 854,134.

To all whom it may concern:

Be it known that I, LELAND CLAPPER, a citizen of the United States, and resident of Two Harbors, in the county of Lake and 5 State of Minnesota, have invented certain new and useful Improvements in Self-Clearing Ore-Pockets, of which the following is a specification.

In the construction of ore docks which 10 receive ore from drop-bottom cars and discharge ore into vessels, it is necessary that the ore bins be of very considerable width, with sloping bottom and having doors covering the discharge openings. A hinged 15 steel chute conveys the ore by gravity from each bin opening into the vessel hatch upon the raising of the bin door. If the door opening is the width of the bin the door becomes very unwieldy, and furthermore, involves 20 a chute of the same width at the top. If two or more doors are used the cost of construction is increased per bin, and in addition, the post or support between the door openings interferes with the flow of ore. 25 To avoid these objections to one wide door or two or more narrower doors, it has been the practice to contract or hopper the discharge opening and use one door of a convenient size at the center. The objection 30 found in practice to this invention is that the ore tends to arch inasmuch as the hopper construction on each side forms an abutment or heel for the arch.

To avoid all the objectionable features of 35 the constructions used hitherto, I propose the simple expedient of hoppering or contracting the bin upon one side only, leaving the other side straight, thus obtaining one opening of a workable size and preventing the 40 arching of the ore, as it is well known that an arch demands two abutments. In practice I have found that ore bins so constructed discharge the ore much more freely than those hoppered on two sides and having the 45 door in the middle.

The invention will be more readily understood by reference to the accompanying drawings, wherein,

Figure 1 is a perspective view of a bin 50 constructed in accordance with my invention, a portion of the front wall thereof being broken away; Fig. 2 is a section on the line 2--2 of Fig. 3, and, Fig. 3 is a section on the line 3--3 of Fig. 2.

Referring more particularly to the drawings it will be seen that the bin may consist

of a vertical wall 10, a front wall 11, provided with an opening 12, of less width than the width of the bin. A floor 13, is provided, this floor sloping downwardly and outwardly as is customary. Located internally of the bin is a deflector, having two angles of inclination. The portion 14, thereof is secured to the floor 13, and extends from the side wall 15 to the edge of the discharge opening 12, directing materials toward such opening in line with their flow. The portion 16, of the deflector extends from the side wall 15, to the upper edge of the deflector 14 and directs materials away from 70 the side wall toward the opening.

By this construction it will be seen that the materials cannot arch over the opening as no support is provided on the side wall 10. Bins so constructed readily clear themselves 75 and the door opening may be of a convenient size.

Obviously the construction is capable of considerable modification and such modifications as are within the scope of my claims 80 I consider within the spirit of my invention.

I claim:

1. In a bin, the combination of walls and a floor, the front wall having a discharge opening extending over a portion only of 85 the width of the bin, said floor being downwardly and outwardly inclined toward said opening and of restricted area at a point contiguous to the opening, and a deflector located in the bin, said deflector having a 90 double angle of inclination, whereby materials are directed toward the restricted discharge opening in substantially horizontal and vertical directions, substantially as described.

2. In a bin, the combination of walls and a sloping floor, one of the side walls extending substantially vertically, the front wall being provided with a discharge opening of a width less than the width of the bin, one 100 edge of said opening substantially coinciding with said vertical wall; and an internal deflector for directing the materials to said opening, substantially as described.

3. In a bin, the combination of walls and a sloping floor, one of the side walls extending substantially vertically, the front wall being provided with a discharge opening of a width less than the width of the bin, one edge of said opening substantially coinciding with said vertical wall, and an internal deflector arranged at an angle to the angle 110

of inclination of the floor and adapted to direct materials to said opening, substantially as described.

4. A bin having a vertical side wall, an inclined side wall, a sloping floor, and a front wall provided with an opening of a width less than the width of the bin, one side of the opening being located adjacent to the plane of said vertical wall, substantially as described.

5. In a bin, the combination of walls, a front and side wall extending substantially

vertically, said front wall being provided with a discharge opening located with one edge substantially coincident with said vertical side wall, said opening being of a width less than the width of the bin, and a deflector at the opposite side of said opening from said vertical side wall, substantially as described.

LELAND CLAPPER.
